JOHN P. AVERY AND W. L. NICHOLS, OF NORWICH, CONNECTICUT.

Letters Patent No. 65,860, dated June 18, 1867.

IMPROVEMENT IN STREET-LANTERNS.

The Schedule referred to in these Letters Patent and making part of the same.

TO ALL WHOM IT MAY CONCERN:

Be it known that we, JOHN P. AVERY and W. L. NICHOLS, both of Norwich, in the county of New London, and State of Connecticut, have invented a certain new and useful Improvement on Street and other Lanterns, of which the following is a full, clear, and exact description, reference being had to the accompanying drawing, forming part of this specification, and in which—

Figure 1 represents an outside elevation of a street-lantern constructed according to our improvement; and Figure 2, a vertical section of the same.

Like letters indicate like parts in both figures.

The nature of our invention consists in providing or constructing the glazed frame of the lantern with tubular passages, so arranged as that they supply the lantern with the air necessary for combustion, without exposing the flame to be wafted or extinguished by the wind. And it further consists in so constructing the several glazed sections or parts with double frames, formed with grooves for the reception of a rope or cord-packing, which answers not only to make the lantern air-tight at the edges of the panes, but forms a soft seat for the glass which is clamped between the double frames by means of set or adjusting-screws uniting said frames.

Referring to the accompanying drawing, A represents the outer main frame or skeleton of the lantern, B its base, and C its ventilator at top. The lower portions of the sides of the frame A are made to form tubes b for a height corresponding to the top of the flame, or thereabouts, or independent tubes, similarly open top and bottom, may be provided. These tubes, b, serve to supply the frame with the air necessary for combustion, and are preferably arranged opposite to each other up the corners or edges of the lantern, so that and by reason of their height relatively to the flame, opposite incoming currents of air, impinging on the flame at or near its top, will have little or no wasting or extinguishing effect on it. Thus arranged, too, the tubes cast no shade nor interfere with the light of the lantern. D E are independent inner and outer pane-holding frames, fitting against and within the several sections or divisions of the main frame, designed to be glazed, including the lid or door. The one of these double frames in the several sections is formed with a groove or grooves, e, in it, in which is arranged a soft rope or cord packing, d, that on insertion may be temporarily held to its place by shellac, but which is afterwards secured by the clamping of the two frames together, with the pane e in between them, by means of adjusting-screws f. This rope or packing runs all round the pane in each section or division, thereby not only forming a soft bed for the glass, to the prevention of fracture, but an air or wind-tight joint to the panes to the steadyng of the flame, and which gives to the lantern an air-tight character.

What we claim as our invention, and desire to secure by Letter Patent, is—

1. The combination, with the lantern-head or frame, of air-tubes b, arranged for supply of air to the flame, substantially as specified.
2. The independent frames D E, in combination with the rope or cord packing d, arranged to fit a groove, e, in the one frame, and clamped or held together to hold the pane in between them, essentially as herein set forth.

JOHN P. AVERY,
W. L. NICHOLS.
